UNITED STATES PATENT OFFICE.

CLARENCE L. PARKER, OF LOS ANGELES, CALIFORNIA, ASSIGNOR OF ONE-HALF TO IRWIN W. ROSS, OF SAN FRANCISCO, CALIFORNIA.

PUMP.

SPECIFICATION forming part of Letters Patent No. 669,590, dated March 12, 1901.

Application filed May 3, 1900. Serial No. 15,357. (No model.)

To all whom it may concern:

Be it known that I, CLARENCE L. PARKER, a citizen of the United States, with post-office address and residence at 643 North Main street, city of Los Angeles, in the county of Los Angeles and State of California, have invented certain new and useful Improvements in Pumps, of which the following is a full, clear, and exact description, reference being had to the accompanying drawings, which form a part of this specification.

My invention relates to certain new and useful improvements in pumps intended more especially for pumping crude oil; and my invention consists in certain features of novelty hereinafter described and claimed.

My present invention relates especially to improvements on my pump which forms the subject-matter of an application, Serial No. 13,522, filed April 19, 1900, in which I show, describe, and claim a cage-valve similar to that herein disclosed.

Figure I is a longitudinal section of the principal parts of my improved pump, showing the valves in their lower position. Fig. II is a side elevation of the operating parts, the pump-tubing being omitted. Fig. III is a longitudinal section showing the valves in their raised position. Fig. IV is a transverse section taken on line IV IV, Fig. III. Fig. V is an enlarged detail side elevation of the cage-valve. Fig. VI is a transverse section taken on line VI VI, Fig. III. Fig. VII is a transverse section taken on line VII VII, Fig. III. Fig. VIII is a detail side elevation of the dog for retaining the cage. Fig. IX is a detail side elevation of the housings and catch for retaining the cageless valve-seat.

Referring to the drawings, 1, 2, 3, and 4 represent sections of the pump-tubing, the top section 1 being coupled to the upper section 2 by a coupling-ring 5, the lower end of said upper section 2 being connected at 6 with an upper housing 7, the upper end of the intermediate section 3 being coupled to said upper housing, as shown at 8, the lower end of the intermediate section 3 being connected with a tube-section 9 of the pump-tubing, as shown at 10, by means of a coupling-ring 11, 50 tube-section 9 of the pump-tubing being coupled at 12 to the upper end of the lower hous-

ing 13, and the lower end of said lower housing being coupled at 14 to the lower section 4 of the pump-tubing. The lower end of the lower housing 13 and the lower section 4 of the pump-tubing are provided with perforations 15 55 16 to admit the inflow of oil to the pumping-valve.

17 represents a pump-rod.

18 represents the valve-cage surrounding 60 the pump-rod, said valve-cage serving to inclose the cage-valve 19. The cage-valve 19 is provided with frictional contact with the pump-rod by means of a two-part clamp 20, partly surrounding the rod, there being 65 springs 21 for connecting the valve with the clamp and affording the necessary pressure of the clamp upon the pump-rod.

22 represents the valve-seat for the cage-valve.

23 represents a ring at the lower end of the valve-cage, said ring having an angular annular recess 24, providing an annular flange 24^a.

25 represents upwardly-extending levers, pivoted at 26 to the upper housing 7, the upper end of said levers terminating in dogs 27, 75 said dogs 27 having recesses 28 receiving the annular flange 24^a on the lower end of the valve-cage, thus normally holding the valve-cage in a fixed position until the dogs are released from the annular flange 24^a. The dogs are provided with upper and lower cam-shaped inner faces 29 30, by which means any projecting part when coming in contact therewith will throw said dogs outwardly, whereby 80 85 the valve-cage may be either engaged or released.

31 represents springs bearing against the outer faces of the dogs, said springs serving to hold the dogs normally in engagement with 90 the valve-cage.

32 represents the pump-plunger, having a valve-seat 33 in its lower end and located between the upper and lower housings.

34 represents the plunger-bracket for depressing the same, said plunger-bracket having an upper seat 35 in the upper end of the plunger.

36 represents the hub of the plunger-bracket, which serves to couple together two 100 sections of the pump-rod.

37 represents a ring having its upper end

riveted at 38 to the hub 36, said ring working within the seat of the plunger and serving as a guide to the plunger-bracket and indirectly to the pump-rod.

5 39 represents an intermediate valve which operates against the lower valve-seat 33 of the plunger and serves to raise the same and which also serves as a coupling for two sections of the pump-rod, as shown at 40 41 and 10 in my former application, hereinbefore referred to.

42 represents my improved standing valve, which is secured at 43 to the upper end of a tube 44, said tube surrounding the pump-rod.

15 45 represents a screw-threaded collar secured to the lower end of the tube 44, and 46 represents a two-part clamp for giving frictional contact between the tubing and pump-rod 17, 47 representing springs for holding 20 the clamp in contact with the pump-rod. The travel of the standing valve is limited by means of a valve-stop 48, said valve-stop being formed of a ring surrounding the pump-rod and having an angular annular recess 49, 25 with which pivoted catches 50 normally engage, said catches 50 being pivoted at 51 to levers 52, the upper end of said levers being pivoted at 53 to the housing 13, which 30 encloses the standing valve. The inner ends 35 of the levers 52 extend into the housing 13, as shown at 54, and are provided with cam-shaped lower ends 55.

56 represents guide-arms or their equivalent extending downwardly from the valve-stop 48, said arms limiting the upward movement of the standing valve by collar 45 coming in contact therewith.

57 represents an agitating-ring, having a

hub 58 for connecting sections of the pump-rod and being provided with perforations 59 40 to allow the ready passage of the oil or other liquid. When it is desired to remove the pump-rod from the tubing, the rod is drawn upwardly until the plunger-bracket 34 comes in contact with the cam-faces 30 on the dogs 45 27, throwing the dogs outwardly from the recess 24 and releasing the cage. At the same time the agitating-disk 57 comes in contact with the faces 55 on the lower ends of the levers 52, throwing them outwardly and releasing the catches from their recess in the valve stop and seat, thus permitting all of the parts to be drawn upwardly and removed from the tubing.

I claim as my invention—

1. In a pump, the combination of the pump-tubing, a pump-rod formed in sections, a plunger, a plunger-bracket, having a hub connecting adjacent sections of the pump-rod, a guiding secured on the hub of the bracket, adapted to operate within the plunger and a valve on the pump-rod beneath the plunger and adapted to raise the same, substantially as set forth. 55

2. In a pump, the combination of the tubing, a pump-rod, a standing valve surrounding the pump-rod, a tubing surrounding the pump-rod one end of said tubing being connected with the standing valve and the opposite end being connected with a friction-clamp 60 surrounding the pump-rod, substantially as set forth. 65

CLARENCE L. PARKER.
